UNITED STATES PATENT OFFICE.

ODILON BRISBOIS, OF CHICAGO, ILLINOIS, ASSIGNOR TO JOHN H. WARE, OF CHICAGO, ILLINOIS.

TELEPHONE SYSTEM.

1,221,135.

Specification of Letters Patent.

Patented Apr. 3, 1917.

Application filed June 12, 1916. Serial No. 103,135.

To all whom it may concern:

Be it known that I, ODILON BRISBOIS, a citizen of the United States, residing at Chicago, in the county of Cook and State of Illinois, have invented certain new and useful Improvements in Telephone Systems, of which the following is a specification.

This invention relates to a telephone system of that class in which a prepay or coin box is used, and to the instruments used in conjunction with such system.

This invention has particular reference to prepay telephone systems of the Bell or manual type.

15 In systems of this character the central exchange is controlled by an operator to whom the calling station, by a signal (as by lighting a lamp), gives notice that a connection is desired to be made.

20 The word "station" as used by me includes the telephone instrument itself, the coin box and the immediately adjacent and interrelated connections.

One of the main objects of the present invention is to so interrelate and interconnect the above named mechanisms that it will be impossible for a calling party to effectively operate the signaling circuit of his station, for the purpose of lighting a lamp or giving 25 any other signal at the central station to secure the attention of the operator and make known the fact that a connection is desired, without first making a deposit of a coin in the coin chute of his coin box.

30 Another object of the present invention is to so interrelate and interconnect the different instruments and mechanisms of each station as to render it unnecessary for the operator at the central station to do any act or 35 thing concerning the disposal of the coin which is deposited at the calling station, other than to make and break the several circuits required to connect a calling with a called station; that is, to make the disposal 40 of the coin which has been deposited in the chute of the coin box automatic in character and determined by the co-acting operations of the party depositing the coin and the central operator.

45 Another object of the present invention is to so interrelate and interconnect the different instruments and mechanisms of each station that before the central operator has answered the signal the party at the calling 50 station can not recover the coin which has

been deposited and after said operator has answered said signal and made the connections necessary to obtain a called party, said party at the calling station can not obtain 55 a return of said coin without calling upon the central operator to disconnect said calling station.

A further object is to so interrelate and interconnect the different instruments and mechanisms of each station that when a conversation is carried on with a called party the circuits over which said conversation is maintained will not include as elements thereof any of the elements or mechanisms entering into the coin controlling devices.

Additional objects will appear from the detail description of the invention and of the features of construction and arrangements of parts and circuits which are shown 60 and described in the specification and claims.

In the drawings,

Figure 1, shows a vertical section of a telephone stand, and a side elevation of a transmitter, a receiver, a receiver hook, and 65 an automatic switch controlled by the position of the receiver hook.

Fig. 2, is a vertical section of a coin box, showing a side elevation of certain constructions forming elements in a system embodying this invention.

Fig. 3, is a vertical section of the coin box which is illustrated in Fig. 2, viewed at an angle of 90 degrees from said Fig. 2, showing some of the elements which are illustrated in Fig. 2, in front elevation.

Fig. 4, is a horizontal section on line 4-4 of Fig. 3, viewed in the direction indicated by the arrows.

Fig. 5, is a rear elevation of a polar relay and a float bar, forming elements in the construction embodying the invention: also showing the armature of said relay and aperture plate on which, (in said aperture), 70 said armature is pivotally mounted.

Fig. 6, shows, in enlarged detail, a side elevation of a float bar and contact leaves mounted thereon forming switches, an edge elevation of one end of contact leaves forming an additional switch, and a vertical section of a portion of partitions of the coin box which form a chute, the several contact leaves standing in their normal position, with the switches formed thereby open.

Fig. 7, illustrates the several parts which 75

are shown in Fig. 6, with a coin in the chute of the coin box, the contact leaves forming said additional switch being closed thereby, and the travel of said coin through said 5 chute arrested.

Fig. 8, illustrates said parts shown in Figs. 6 and 7, with said coin on the float bar of the coin box, the contact leaves thereon forced down by the weight of said coin, closing 10 said switches.

Fig. 9, shows an electrical diagram of an arrangement of parts and connections at a calling station embodying features of the invention, and certain of the elements at a 15 central station which coöperate therewith, all said parts being in position with the telephone receiver off its hook, with a coin in the chute of the coin box, (as illustrated in Fig. 7) and with a signal showing at central 20 station.

Fig. 10, is a like diagram of the parts illustrated in Fig. 9, with said receiver off its hook, with the central operator plugged in, said signal cut out, said coin on the float bar, 25 (as illustrated in Fig. 8) and the several contact leaves which are mounted on said float bar forced down by the weight of said coin to close the switches formed thereby.

Fig. 11, is a like diagram of the parts 30 illustrated in Figs. 9 and 10, with the telephone receiver returned to its hook, closing the switch controlled thereby, with the central operator plugged in, said signal cut out, and said coin on the float bar, as illustrated 35 in Fig. 10.

When the several parts and circuits are 40 in condition as illustrated in Fig. 10, the removal of the plug at the central station by the operator will close an energizing circuit 45 which will move the float bar to discharge the coin thereon from the coin box at the calling station; that is, will return said coin to the calling party; and when the several parts and circuits are in the position which is 50 illustrated in Fig. 11, the removal of said plug will close an energizing circuit which will move said float bar to deposit said coin in the safe of said coin box.

A reference letter applied to designate a 55 given part indicates said part throughout the several figures of the drawing wherever the same appears.

X represents a wall of a pay station box or shell, which is attachable to base X' 55 (Figs. 2, 3 and 4). X², X³, represent partitions which are attached to base X' and between which are the coin chute Y and branches y, y'. X⁴ represents a bracket which is secured to the base X', and on said 60 bracket the electromagnet coils and float bar hereinafter described are mounted. X⁵ represents the heel iron of said electromagnet. X⁶ (Figs. 2, 3, and 5), represents a rectangular plate having apertures X⁷ 65 therein and an aperture corresponding in

contour with the outline of armature O. X⁸ represent screws in the horizontal arm of bracket X⁴, on which screws plate X⁶ is adjustably mounted, being held in an adjusted position by nuts X⁹. Z represents a tray in 70 front of the box into which said branch y is adapted to discharge a coin. Z' represents a safe in box X into which the branch y' of the coin chute is adapted to discharge a coin. The word "coin" as used in this specification includes a token or other metallic currency. 75

A, Fig. 1, represents a telephone standard, and a the base thereof. B represents a transmitter on standard A; C a receiver; D a receiver hook; d the pivot on which receiver hook D turns; E a vertically movable post; e insulating material at the lower end of post E; and F a switch consisting of the contact points f and f' separated from each 80 other and from the base a by the insulating material e'. G represents a switch consisting of the contact points g, g' which are mounted on flexible leaves separated from each other and from partition X³ of the box 90 X, by insulating material (see Fig. 2). H represents a switch which comprises the contact point h on a flexible leaf which is mounted on the float bar I and contact point h' which is mounted on said float bar. J 95 represents a switch comprising the contact points j, j', which are respectively secured on flexible leaves which are attached to the float bar I. K represents an aperture in partition X³ through which the upper end of bar or 100 abutment I' on float bar I extends, into the chute Y, to form a coin arrester.

The contact leaf above the float bar I, and secured thereon, is mechanically connected with the upper one of the contact 105 leaves of switch J, (secured to the under side of said float bar), by means of the plug or post M, which is made of insulating material.

The float bar I is secured to the armature 110 of magnets N, N' and said armature is pivotally mounted by means of the pivots i, plate X⁶, screws or bolts X⁸ and nuts X⁹, hereinbefore described, on bracket X⁴, and said armature is moved from its neutral and normal position when one or both of the electromagnets N, N', are energized, carrying therewith said float bar. 115

O, Figs. 2, 4, 5, 6, 7, and 8, represents the armature to the electromagnets N, N'. P, 120 P', P², represent line terminals. p, (see diagrams 9, 10, 11) represents an electric conductor attached to terminal P and electrically connecting said terminal to ground P³. p' and p² are line wires attached to terminals P' P² respectively and extending to a 125 central station where, as illustrated in the drawings, they are attached to jack springs Q, Q'.

So much of a central station equipment 130

which I consider necessarily forms a part of the instrumentalities required in the embodiment of this invention, is illustrated by diagrams in Figs. 9, 10, 11. These parts 5 are well known in the art and are in common use, and as they, *per se*, form no part of the invention they are not illustrated other than by said diagrams.

In said central station equipment, Q, Q', 10 represent jack springs. q, represents a conductor which is attached to a terminal with which jack q is in electrical contact when plug R is not inserted in the jack. The conductor q is represented as connected to the coil q' of an electromagnet from which electric conductor q² extends to the battery q³ and by conductor q⁴ to ground q⁵. q⁶ represents the armature to the electromagnet of coil q²; and q⁷ represents a conductor 15 which is in electrical connection with ground q⁴, and armature q⁶. q⁸ represents a terminal which is in electrical connection, by means of armature q⁶, with conductor q⁷ when coil q² is energized and said armature is thereby drawn into the position 20 which is illustrated by full lines in Fig. 9. q⁹, represents an electric conductor which is in electric connection with terminal q⁸ and with signal lamp Q². Q³ represents an electric conductor attached to signal Q² and battery Q⁴, and Q⁵ represents a conductor from battery Q⁴ to ground Q⁶. R' represents a ring forming an electric conductor. R² represents an electric conductor connecting ring R' with ground R³. r, r', r², 25 represent electric conductors contained in a flexible cord and respectively attached to the several insulated divisions r³, r⁴, and r⁵, of plug R. Said conductors are in electric contact at the other ends thereof in like manner with a duplicate plug R. When the plug R is inserted in ring R', and springs Q, Q', the part r³ is in electrical connection with spring Q, part r⁴ is in electrical connection with spring Q' and part r⁵ is in 30 electrical connection with ring R'. After the central operator has inserted plug R as last above recited and obtained from the calling station the necessary information, the above named duplicate of plug R is 35 properly inserted to obtain a party desired.

S represents a conductor which is in electrical connection at one end with terminal P', and at the other end with the transmitter B. S' represents a conductor in electrical connection at its ends with transmitter B and receiver C, and S² represents a conductor which is in electric connection at its ends with one pole of transmitter C and with terminal P². T represents a conductor which connects terminal P and the leaf of switch F on which the contact point f is mounted, T' a conductor which connects the leaf of said switch on which contact f' is mounted with the leaf of the switch J on

which the contact point j is mounted, and T² a conductor which connects contact j' with the coil of electromagnet N. T³ represents a conductor which is in electric connection with coils N and N' and also with conductor T². t represents a conductor which is in electric connection at one end with coil N and at the other end with the leaf of switch H on which the contact point h is mounted, and t' represents a conductor from said last named leaf to leaf g of switch G, (forming at times a continuation of conductor t), (as in diagram Fig. 9). t² represents a conductor in electric connection at its ends with leaf g' of said switch G and 75 with terminal P. t³ represents a conductor which is in electric connection at one of its ends with one end of coil N' and at its other end with the terminal P'. 80

U, Fig. 4, represent springs yieldingly 85 holding float bar I in its normal and neutral position (adapted to receive a coin thereon). V represents a coin.

When a coin is deposited in chute Y, during its passage down said chute, it comes 90 into engagement with the leaf of switch G on which the contact point g is secured (see Figs. 2, 6, 7, and 8) and moves said leaf to force said contact point into electrical engagement with contact point g' of said 95 switch. The sub-station circuit which is shown by heavy lines in Fig. 9, is thereby closed, at the substation, and when plug R is not inserted in the jack the circuit (which I will designate as the calling circuit) and 100 which includes the substation circuit last above named, is closed. This calling circuit comprises (starting from ground P³ at the substation), the conductor p to terminal P, from thence conductor t² to switch G, 105 through contact points g, g', of said switch G to conductor t' thence on conductor t to coil N, through said coil, thence on conductor t³ to coil N' thence on conductor t³ to terminal P', thence on conductor p' to 110 jack spring Q at the central station, thence on conductor q to and through coil q² to battery q³ and from thence to ground q⁵. The closing of the above traced circuit, which is energized by said battery q³ moves armatures q⁶ to close the central station local 115 signaling circuit which comprises ground q⁵, conductor Q³ battery Q⁴ conductor Q⁵, and ground Q⁶. The signal lamp Q² is thereby lighted to attract the attention of the central operator. 120

The energizing of the above traced calling circuit in addition to lighting the lamp Q² in the manner above stated, to attract the attention of the central operator, moves the 125 float bar I, (by the energizing of coils N, N'), so that the abutment I' moves in chute Y into the pathway of the coin V, and said coin is thereby arrested, substantially in the position in which it is illustrated in Figs. 7 130

and 9, and remains in said arrested position until the operator inserts plug R between jacks Q, Q'. It is thus beyond the control of either the party at the calling station or the central operator until after said plug is inserted between said jack springs. When the central operator inserts said plug R between said jack springs, said springs are moved away from the contact points or terminals of conductors q, q', and said calling circuit is thereby broken. Thereupon the coils N, N', cease to be energized and float bar I is returned to its normal or neutral position, as by springs U. On the return of the float bar to its normal position the abutment I' moves from coin V and said coin thereupon resumes its travel, in chute Y and is delivered onto the flexible leaf on the upper side of said float bar I, by its weight closing switches H and J. When the coin has been delivered as last above set forth, it requires the conjoint action of the party at the calling station and the central operator to discharge said coin therefrom in a determined direction. This discharge is effected by the central operator withdrawing the plug R from the jack, and the one of the branch chutes y y' into which it is discharged is determined by the party at the calling station. That is, if the party at the calling station returns his receiver C to hook D the coin is discharged into chute y' and safe Z'. If, however, plug R is removed from between springs Q, Q', before receiver C is returned to hook P, the coin is discharged into branch chute y and from thence into tray Z. The circuit which is closed and energized to return the coin to the party at the calling station is shown in diagram in Fig. 10, and comprises the following elements; starting from ground P³, at the calling station, thence on conductor p to terminal P', thence on conductor t⁴ to switch H through said switch to conductor t, thence to and through coil N, thence, on conductor T³ to and through coil N', thence through said coil to conductor t³, thence to terminal P', thence on conductor p' to spring Q, thence on conductor q, through coil q², to and through battery q³, and to ground q⁴.

It will be observed that the coils N, and N', on the closing of this last traced circuit are energized the same as in the energizing of the calling circuit and the float bar I is moved in the same direction as in the energizing of said coils by the closing of said calling circuit; but as the coin has passed the abutment I' and is on the leaf above said float bar I, said repetition of the movement of said float bar moves it out from under said coin so that the same is discharged into the branch chute y and from thence, is delivered into the tray Z. This circuit I call the return circuit as the coin

is returned to the calling party by the closing and energizing thereof.

When the receiver C is returned to its hook D the contact points f, f', are brought into electrical contact, closing switch F. 70 The sub-station circuit which is marked in heavy lines in Fig. 11, is thereby made and when plug R at the central station is removed from between springs Q, Q', it is energized. This sub-station circuit comprises starting from ground P³, conductor p, terminal P, conductor T. Switch F, conductor T', switch J, conductors T² and T³, coil N', conductor t³ terminal P'; and it forms a part of a circuit which I call the 80 collecting circuit. Said collecting circuit comprises also conductor p', jack spring Q, conductor q, coil q², battery q³ and to ground q⁴.

Energizing of the coil of electromagnet 85 N' moves the float bar I so that the coin thereon is discharged into branch chute y' and from thence is delivered into the safe Z' of the coin box.

It will be observed that coil q² at the central station is energized in the closing of the calling circuit, the returning circuit and the collecting circuit as said circuits are above traced, and thereby the signal circuit at the central station is closed and energized each 95 time, and the central operator is thereby advised, by the lighting of the central lamp Q², of the closing and operation of said circuits.

I claim:—

1. A telephone system comprising a central station and sub-stations, metallic conductors between said central station and said sub-stations, a signal, a battery, and an electric conductor at said central station arranged to form elements of electric circuits having additional elements at the respective sub-stations, said circuits normally closed at the central station and normally open at said sub-stations, means at the central station to open said circuit, coin boxes at sub-stations, a float bar, a coin arrester and a coin chute in each of said boxes, means to yieldingly hold said float bar and said coin arrester in neutral positions, said float bar 100 adapted to obstruct and said arrester adapted not to obstruct the movement of a coin when in said neutral positions; said additional elements at the sub-station comprising 105 a polarized relay and coin actuated means to close said circuit; whereby, on the deposit of a coin in the chute of a box at a determined sub-station, the circuit between said sub-station and said central station is closed, and said signal and polarized relay 110 are energized, to indicate said closing and to move said coin arrester to obstruct a coin and prevent its delivery to the float bar and on the operating of said circuit opening 115 means at the central station said circuit is 120 closed, and said signal and polarized relay 125 are energized, to indicate said closing and to move said coin arrester to obstruct a coin and prevent its delivery to the float bar and on the operating of said circuit opening 130 means at the central station said circuit is

opened and said coin arrester is released from its moved position to return to its neutral position, and said coin is discharged from said arrester and obstructed by said 5 float bar.

2. A telephone system comprising sub-stations and a central station, coin boxes at said sub-stations, and a battery, a signal, a switch and means to open said switch at said 10 central station, coin chutes, polarized relays, and float bars, in said boxes, coin arresters and coin controlled switches to said chutes, and electric conductors arranged to connect said sub-stations to said central station and 15 form circuits in which said battery, signal, switches and polarized relays are elements, said switch at said central station being normally closed and said switches at said sub-stations being normally open, said sub- 20 station switches arranged to be closed by a coin in the chute related thereto to close the circuit from the sub-station where said coin is deposited to said central station, means to yieldingly hold said float bars and arresters 25 in a neutral position, said float bars adapted to obstruct movement of a coin when in said neutral position, and said relay arranged to move said arresters from said neutral position when said circuits are closed, to ob- 30 struct the movement of a coin to said float bars.

3. A telephone system comprising a central station and sub-stations, metallic conductors between said central station and the 35 respective sub-stations, a signal, a battery, a battery conductor, means to ground said conductor, and means to disconnect said ground at said central station, said signal, battery and conductor arranged to form elements in 40 circuits extending to said sub-stations and there having additional elements therein, comprising a polarized relay and coin controlled means to ground said circuits, coin boxes at said sub-station, coin chutes, float 45 bars, and coin arresting means connected to said float bars, said float bars adapted, when in neutral positions, to obstruct coins, and to be moved from said neutral positions by said relays, and said coin arresting means 50 being arranged so that movement of the connected float bar in a determined direction from its neutral position moves said coin arresting means to obstruct a coin: whereby the deposit of a coin in a chute at a given 55 sub-station closes the circuit between said station and said central station to energize the polarized relay therein, and arrest said coin and also to energize said signal at said central station, and on the opening of said 60 circuit by disconnecting said ground at said central station, said float bar and coin arresting means return to a neutral position and permit the passage of said coin to said float bar.

4. A telephone system comprising a cen-

tral station and sub-stations, a signal at said central station and means adapted to make and to break an electric circuit at all of said stations, said central station connected to said sub-stations by electric conductors 70 forming elements in circuits of which said signal and said means to make and to break said circuits are elements, the said circuit being normally closed at said central station and normally open at said sub-stations, means to energize said circuits, coin boxes at 75 said sub-stations, a coin chute, a float bar, a polarized relay and means to arrest a coin before said coin is in contact with said float bar in each of said coin boxes, means to yieldingly hold said arresting means in a neutral position when said circuits are open, said relays arranged to move said arresting means from said neutral position on said circuits being closed and said means to make 80 and to break said circuits at the sub-stations being arranged to be actuated by a coin in said chutes to close said circuits.

5. In a telephone system, the combination of talking and listening instrumentalities, 90 signaling mechanism, a prepay box, a coin chute, an electric switch actuatable by a coin in said chute, a float arm and a polarized relay in the prepay box, means to arrest a coin connected to said float arm, electric 95 switches on said float arm, interconnections between said first named switch and between the switches on said float arm, respectively, and the signaling mechanism and said polarized relay arranged to cut out said signaling 100 mechanism until a coin successively closes said switches and thereby successively arrests a coin and releases it to said float arm.

6. In a telephone system, the combination of talking and listening instrumentalities, 105 a signal and signaling mechanism operable by a current on a determined circuit, interconnections between said talking and listening instrumentalities and said signaling mechanism to break said circuit when said talking and listening instrumentalities are 110 in operable position, and to close said break when said talking and listening instrumentalities are separated from said operable position, a prepay box, a chute and a float 115 arm in said prepay box, a polarized relay for actuating the float arm to throw the same either into a position for returning a coin or into a position for collecting a coin, movable contacts, operable by a coin deposited in said chute, and additional movable contacts operable by a coin obstructed by said float arm, interconnections between 120 said first named contacts and the signaling mechanism arranged to render the latter in- 125 effective to deliver a current to said signaling mechanism and polarized relay until a coin is deposited in said chute and between said additional contacts to render said determined circuit ineffective to deliver a current 130

to said polarized relay until a coin is obstructed by said float arm, said interconnections with the switches on said float arm arranged to determine the direction of delivery of the coin when released from being obstructed by the float arm by the position of said listening instrumentalities.

7. A telephone system comprising a central station and sub-stations, metallic conductors between said central station and said sub-stations, interconnections between said float bar and talking and listening instrumentalities at said stations, a signal at said central station, a battery and a conductor, and means whereby when said conductor is grounded said battery forms the energizing element in a circuit, having additional elements at a sub-station, means at said central station to open said circuit, said sub-stations respectively provided with a coin chute, means to arrest a coin and a float bar, said arresting means and said chute adapted to successively deliver a coin to said float bar, a polarized relay comprised in said additional elements and arranged to actuate said arresting means, means to ground said above named circuit by a coin deposited in said chute, to arrest said coin before the same is delivered to said float bar, means to yieldingly maintain said float bar in a neutral

position when said circuit is open, to obstruct said arrested coin on the delivery thereof thereto, and interconnections between said float bar and said talking and listening instrumentalities to determine the direction of discharge of said coin obstructed by said float bar when said polarized relay is energized. 35

8. In a prepay box provided with a coin chute, the combination of a float arm, pivoted to swing about an axis, said float arm provided with an abutment movable into the path of a coin deposited in said chute, a polarized relay, an armature for the same, a connection between the armature and a float arm, whereby the float arm and abutment are deflected according to the movement of the armature, leaf contacts mounted adjacent to said chute, and adapted to be actuated to close said contacts by a coin deposited in said chute, and a plurality of leaf contacts mounted on said float arm, a coin seat on one of said leaf contacts, and a mechanical connection between two of said leaf contacts whereby they are forced to move in unison. 40 45 50 55

ODILON BRISBOIS.
